UNITED STATES PATENT OFFICE.

TRUMAN L. FIRESTONE, OF AKRON, OHIO.

MACHINE FOR HEADING INSULATORS.

SPECIFICATION forming part of Letters Patent No. 759,429, dated May 10, 1904.

Application filed March 21, 1903. Serial No. 148,869. (No model.)

To all whom it may concern:

Be it known that I, TRUMAN L. FIRESTONE, a citizen of the United States, residing at Akron, in the county of Summit and State of Ohio, have invented certain new and useful Improvements in Machines for Heading Insulators, of which the following is a specification.

This invention relates to machines for heading insulator-tubes; and the object is to provide a simple construction of machine for automatically forming the heads upon tubes designed to be used for electrical insulators.

With the above object in view the invention consists in the novel features of construction hereinafter fully described, particularly pointed out in the claims, and clearly illustrated by the accompanying drawings, in which—

Figure 1 is a top plan view of a machine constructed in accordance with my invention; Fig. 2, a vertical transverse sectional view of the same, taken on the line 2 2 of Fig. 1 looking in the direction of the arrow; Fig. 3, a vertical longitudinal sectional view on the line 3 3 of the same figure; Fig. 4, a vertical transverse sectional view on line 4 4 of said Fig. 1; Fig. 5, a side elevation of the operating cam-wheel, and Fig. 6 a detail view of the operative connection between the two operating-shafts of the carrier-actuating mechanism.

Referring now more particularly to said drawings, 1 designates the table or bed, intermediately of the ends of which the transversely-extending supports 2 are arranged, in which the wheels 4 are mounted. Passing around said wheels 4 is a carrier-chain 5, provided with pockets or receptacles 6 to receive the tubes.

The feed for the carrier consists of the following mechanism: Mounted in supports 7 at one end of the table is a driving-shaft 8, which may be driven by any desired power, having fixed thereon a gear 9, which meshes with a larger gear 10, carried by a shaft 11, mounted in suitable supports 12, both of said shafts extending transversely of the bed or table of the machine. Upon said shaft 11 is a cam-wheel 13, provided with a cam 14, adapted to actuate a rock-shaft 15, mounted in suitable supports 16 by contact with a lat-

erally-extending arm 17, carried by said shaft and disposed in the path of said cam. Attached to the opposite end of said shaft 15 is a crank-arm 18, to which a link 19 is pivotally attached, said link at its opposite end being connected by a pin-and-slot connection with a crank-arm 20, carried by one end of a shaft 21, suitably mounted, and provided at its opposite end with a crank-arm 22, with which a link 23 has a pin-and-slot connection, as illustrated in Fig. 4. Said link 23 at its opposite end is pivotally attached to an actuating-pawl 24, having an engaging portion 25, adapted to engage the pins of the links of the chain and actuate said chain. Attached to a suitable support is a stop-pawl 26, said pawl serving to prevent the carrier when the machine is running at a high rate of speed from carrying the tube beyond the proper point in front of the die. This pawl is connected with its support by a series of levers 27, as illustrated in Fig. 4. When the cam 14 contacts with the arm 17, shaft 15 is partially rotated, which movement is communicated to shaft 21, causing the feed-pawl 24 to actuate the carrier to bring one of the tubes carried thereby in proper position to be headed by the dies, which will be hereinafter fully described. The feed mechanism is returned to its normal position after advancing the carrier by a coiled spring 28.

Heading mechanism.—Mounted to one side of the carrier is the stationary die 29, having a central opening of proper size to receive the tube and permit the formation of the head thereon and formed with a steam-chamber 30, surrounding said opening, and provided with the steam-inlet pipe 31 and outlet-pipe 32. Mounted to slide in supports 33, disposed on the opposite side of the carrier, is a plunger 34, connected by a pitman 35 with a crank-disk 36 on shaft 11, said plunger carrying the movable die 37, which as the plunger is reciprocated moves transversely across the carrier through the pockets or receptacles thereof. The tubes are one by one, as the carrier is actuated, forced into the stationary die and headed by the movable plunger and die carried thereby.

Ejecting mechanism.—For ejecting the

tubes from the stationary die after the heads have been formed thereon the following mechanism is provided: Mounted in rear of the stationary die is a support 38, carrying a 5 guide-rod 39, which is disposed longitudinally of the die and is positioned in the central opening thereof, extending from end to end of the die. Sliding in said support 38 and upon rod 39 is a sleeve or tube 40, having at one end 10 a cross-head 41, carrying two longitudinally-extending rods 42, disposed parallel with the sleeve and extending loosely through a cross head or bar 43, carried by the plunger 34, said rods being provided with nuts 44 on the ends 15 thereof which project through the cross-head of the plunger. The plunger in its movement to and from the stationary die slides on said rods, and when it has moved a sufficient distance on its rearward movement from the 20 stationary die to bring the cross-head thereof in contact with nuts 44, which constitute stops, the independent movement of the plunger relative to the rods is checked and said rods are moved with the plunger, moving the 25 sleeve or tube 40 through the stationary die and forcing the headed insulator-tube therefrom upon the carrier. Upon the forward movement of the plunger to head another tube said sliding sleeve is returned to its normal 30 position by a spring 45, connected with the cross-head 41 and with a suitable support independent thereof, a stop or buffer 46 being provided to check said movement of the sleeve in a reverse movement to its movement 35 in ejecting the headed tube. The movable die is provided with a central opening to receive the end of the guide-rod 39, which rod acts as a stop to limit the forward movement 40 of the die.

The stationary die is made of either brass or bronze, as the material of which the tubes are formed does not adhere to these metals as it does to other metals, and by heating this die, as set forth, the amount of lubricant necessary to be used is materially decreased, as 45 in the case of a die which is not heated it is necessary to use a considerable quantity of oil, the result being a deterioration of the glaze upon the tubes, thus causing a rough 50 and uneven surface when the insulator-tubes are burned.

Carrier-elevating mechanism.—The movable die being larger than the tube to be headed, it is necessary to provide some means 55 for raising the carrier with the tube, so that said tube can be engaged and centered by the die, and to accomplish this the following mechanism is provided: Pivoted intermediate of its ends beneath the upper portion of 60 the carrier is a lever 47, having a laterally-extending stud 48 at one end, which is engaged by a crank-arm 49 on the end of a rock-shaft 50, mounted in suitable supports 51 upon the table or bed and extending longitudinally thereof, said shaft at its opposite

end being provided with a crank-arm 52, disposed in the path of a cam 53 on cam-wheel 13. When said cam comes in contact with the arm 52, the shaft is rocked and the lower end of lever 47 depressed, the opposite end thereof being raised, elevating the pocket of the carrier containing the tube to be headed, bringing said tube in position to be centered by the movable die. As soon as one end of the tube is received in the opening of the movable die and the other end is started into the stationary die the lever 47 is released and returned to its normal position, this return movement being effected by a spring 54, thus permitting that section of the carrier which 75 has been elevated to drop to its normal position and the movable die to pass over the same.

From the above description it is believed the operation of the machine will be fully understood, it being necessary to simply state 80 that the prepared tubes of proper length are placed upon the carrier and fed thereby one by one to the proper position to be moved into the stationary die by the movable die and headed and then ejected by the movable 85 sleeve. The position of the stop or buffer 46 determines the length of the tubes, as the position of the sleeve 40, against which the rear end of the insulator-tube abuts when moved into the stationary die, is in turn fixed by the 90 position of the stop.

The lower portion of the carrier is supported and prevented from sagging by a plate or support 56 positioned therebeneath, as 95 shown in Fig. 4.

Having thus fully described my invention, what I claim as new, and desire to secure by Letters Patent, is—

1. In a machine for heading insulator-tubes, a stationary die, a carrier formed with transversely-extending pockets to receive the tubes, means for imparting motion to said carrier to bring said pockets containing the tubes successively in operative position relative to the stationary die, a movable die adapted to move 105 said tubes from the pockets of the carrier into the stationary die and form the head thereon, and means for reciprocating said movable die.

2. In a machine for heading insulator-tubes, a stationary die, a carrier for the tubes, means for imparting motion to the carrier to bring the tubes successively in operative position relative to the stationary die, a movable die adapted to move said tubes from the carrier 110 into the stationary die and form the head thereon, means for actuating said movable die, and ejecting means for ejecting the headed tubes from the stationary die operated by the movable die.

3. In a machine for heading insulator-tubes, a stationary die, a carrier adapted to convey the tubes to and from the stationary die, means for actuating the carrier, a movable die for moving said tubes from the carrier into the 115

stationary die and forming the head thereon, means for actuating the movable die, and ejecting means for ejecting the headed tubes from the stationary die and depositing the same 5 upon the carrier.

4. In a machine for heading insulator-tubes, a stationary die, a carrier for conveying the tubes to the stationary die, operating means for said carrier, a movable die for moving said 10 tubes from the carrier into the stationary die and forming the head thereon, means for actuating the movable die, an ejecting device for removing the headed tubes from the stationary die, and an operative connection between the ejecting device and the movable die whereby said movable die upon its return movement actuates the ejecting device to eject the headed tube.

5. In a machine for heading insulator-tubes, 20 a stationary die, a carrier for conveying the tubes to the stationary die, operating means for said carrier, a movable die for moving said tubes from the carrier into the stationary die and forming the head thereon, means for actuating the movable die, an ejecting device operated by the movable die for ejecting the headed tubes from the stationary die, and means for restoring the ejecting device after 25 it has been operated to eject the tube.

30 6. In a machine for heading insulator-tubes, a stationary die, a carrier for conveying the tubes to the stationary die, operating means for said carrier, an ejecting device for ejecting the headed tubes from the stationary die, a reciprocating die for moving the tubes into the stationary die and forming the head thereon having a sliding connection with said ejecting device, means for actuating the reciprocating die, and means for preventing independent 40 movement of the reciprocating die and ejecting device upon the return movement of the former.

7. In a machine for heading insulator-tubes, a stationary die, a carrier for conveying the 45 tubes to the stationary die, operating means for the carrier, an ejecting device movable longitudinally for ejecting the headed tubes from the stationary die having a longitudinally-extending arm, a reciprocating die for moving the tubes from the carrier into the stationary die and forming the head thereon having a sliding connection with said arm, a stop for 50 limiting the independent rearward movement of said die on said arm, and means for actuating the reciprocating die.

8. In a machine for heading insulator-tubes, a stationary die, a carrier for conveying the tubes to the stationary die, operating means for the carrier, an ejecting device comprising 60 a member movable in said stationary die, a cross-head on said member, parallel longitudinally-extending arms carried by said cross-head, a restoring-spring connected with said cross-head, a reciprocating die for moving said 65 tubes from the carrier into the stationary die

and forming the head thereon, a cross-head carried by said die sliding on said arms of the ejecting device, stops on said arms rearward of the cross-head of the die, and means for actuating the reciprocating die. 70

9. In a machine for heading insulator-tubes, a stationary die, a transversely-arranged carrier on the entrance side of the stationary die adapted to convey the tubes to position to enter said die, means for actuating said carrier, 75 an ejecting device arranged on the opposite side of the die and movable therethrough for ejecting the headed tubes, means for actuating said ejecting device, a movable die arranged to reciprocate across said carrier for 80 moving the tubes therefrom into the stationary die and forming the head thereon, and means for actuating the movable die.

10. In a machine for heading insulator-tubes, a stationary die, an endless carrier for 85 conveying the tubes to the stationary die, a pivoted lever arranged beneath the upper portion of the carrier for elevating that portion thereof carrying the tube to be operated on, means for operating the carrier, means for operating the lever, a movable die for moving said tubes from the carrier into the stationary die and forming the head thereon, and means for actuating the movable die. 90

11. In a machine for heading insulator-tubes, a stationary die an endless flexible carrier for conveying the tubes to the stationary die, an intermediately-pivoted lever arranged beneath the upper portion of the carrier for elevating that portion thereof carrying the 100 tube to be operated on having a laterally-extending stud in its lower end, a rock-shaft having an arm at one end engaging said stud and a crank-arm at its opposite end, a cam-disk for actuating said crank-arm, means for 105 operating the cam-disk, a movable die for moving the tubes from the carrier into the stationary die and forming the head thereon, and means for actuating the movable die.

12. In a machine for heading insulator-tubes, a stationary die, a carrier-chain for conveying the tubes to the stationary die, a pawl engaging the links of the chain for feeding the carrier, a rock-shaft having a crank-arm at each end, a cam-disk for actuating the crank-arm at the rear end of the shaft, means for actuating the cam-disk, a shaft mounted adjacent to the forward end of the first-mentioned shaft having crank-arms at each end thereof, an operative connection between one of said 115 arms and the crank-arm at the forward end of said first-mentioned shaft, an operative connection between the other of said arms and the pawl, a movable die for moving the tubes from the carrier into the stationary die and forming 120 the head thereon, and means for actuating the movable die.

13. In a machine for heading insulator-tubes, a stationary die, a carrier for conveying the tubes to the stationary die, means for 125

actuating the carrier, a stop mechanism for preventing the carrier from conveying the tube to be operated on past operative position with respect to the stationary die, a movable die 5 for moving the tubes from the carrier into the stationary die and forming the head thereon, and means for actuating the movable die.

14. In a machine for heading insulator-tubes, a stationary die, a carrier for conveying the tubes to the stationary die, a movable die for moving the tubes from the carrier into the stationary die and forming the head thereon, an ejector for ejecting the headed tubes and depositing the same upon the carrier, means for 15 actuating the carrier to bring the tubes successively in operative position arranged to permit the carrier to remain stationary during the operation of the movable die in removing the tube therefrom and the operation of the ejector 20 in depositing the headed tube thereon, and operating means for the ejector and movable die.

15. In a machine for heading insulator-tubes, a stationary die to receive the tubes, a carrier adapted to convey the tubes to said die,

means for actuating said carrier, a movable die 25 adapted to move said tubes into the stationary die to form the head upon the tubes, means for actuating said movable die, and ejecting means actuated by the movable die for returning the tube to the carrier after it 30 has been headed.

16. In a machine for heading insulator-tubes, a stationary die to receive the tubes, a carrier adapted to convey the tubes to said die, means for actuating the carrier, a movable die 35 adapted to engage said tubes and move the said tubes into the stationary die to form the head thereon, means for actuating said movable die, and means for raising the carrier with the tube to be acted upon to bring said tube in position 40 to be engaged by the movable die.

In testimony whereof I affix my signature in presence of two witnesses.

TRUMAN L. FIRESTONE.
